[57] CLAIM

The ornamental design for a combined stadium seat cushion and storage compartment, as shown and described.

DESCRIPTION

FIG. 1 is an isometric view of the front top and one side of a combined stadium seat cushion and storage compartment shown in position of use it being understood that broken line showing of the support of a stadium, arena or coliseum seat is for illustrative purposes only and forms no part of claimed design.

FIG. 2 is an enlarged top view of the combined stadium seat cushion and storage compartment.

FIG. 3 is a left side view of the combined stadium seat cushion and storage compartment.

FIG. 4 is a back view of the combined stadium seat cushion and storage compartment.

FIG. 5 is a right side view of the combined stadium seat cushion and storage compartment.

FIG. 6 is an enlarged front view of the combined stadium seat cushion and storage compartment; and,

FIG. 7 is an enlarged bottom view of the combined stadium seat cushion and storage compartment.

FIGS. 2-7 illustrate the appearance of the combined stadium seat cushion and storage compartment before being put into use as in FIG. 1.
